UNITED STATES PATENT OFFICE.

AARON FUTTERMAN, OF NEW YORK, N. Y.

WELDING-TOOL.

No. 899,864.

Specification of Letters Patent. Patented Sept. 29, 1908.

Application filed April 29, 1908. Serial No. 429,858.

To all whom it may concern:

Be it known that I, AARON FUTTERMAN, a citizen of the United States of America, residing at New York, in the borough of the Bronx, county and State of New York, have invented certain new and useful Improvements in Welding-Tools, of which the following is a specification.

This invention relates to an improved 10 welding tool in which a mixture of acetylene and oxygen is employed.

The novel features of the invention will be hereinafter described and claimed.

In the accompanying drawings, Figure 1 15 represents a side-elevation of my improved welding tool, Fig. 2 is a section on line 2—2, Fig. 1, Fig. 3 is a vertical transverse section through the mixing nozzle, on line 3, 3, Fig. 1, and Fig. 4 is a vertical transverse section 20 on line 4, 4, Fig. 3.

Similar letters of reference indicate corresponding parts.

Referring to the drawings, *a* represents the acetylene tube, which is provided with 25 a stopcock *a*¹ near its ingoing end, and which is connected by a suitable hose *a*² with an acetylene generator of any approved construction, so that the acetylene gas is supplied under pressure to the supply-tube *a*. 30 Near the stopcock *a*¹ is arranged a cylindrical receiver *b*, which is filled with asbestos fiber for retarding the flow of acetylene gas. The receiver *b* is connected by the tube *a* and a nipple *a*³ with the cylindrical main-portion 35 of a nozzle *d*, to the lower end of which is screwed a nozzle *n*, of which a number are provided, having different sizes of openings so as to obtain flames of larger and smaller size, according to the metallic objects which 40 are welded together.

A hose *e* is connected with a fountain containing oxygen under pressure, and with tube-sections *e*¹, *e*² which lead to a stuffing-box *e*³ at the upper part of the cylindrical body of the nozzle *d*, the oxygen being supplied through a central opening *o* at the inner end of the nozzle, while the acetylene is supplied through a side-opening *o*¹ in the nozzle. The acetylene-supply tube is made 50 larger than the oxygen-supply tube, so that

a larger quantity of acetylene is conducted to the nozzle than the quantity of oxygen supplied. The oxygen tube *e*² is provided with a stopcock *e*⁴ so as to regulate the supply of oxygen. The oxygen-supply tube *e*¹ 55 is supported in standards *f*, which are attached to hubs *f*¹ on the tubular receiver *b* at the ends of the latter.

The upper ends of the standards *f* are extended above the oxygen-supply tube *e* and one is provided with an eye, while the other standard is provided with a forked end *f*² for inserting an auxiliary supply-tube *g*, which is curved in downward direction near the nozzle *n* so as to terminate in a smaller 60 nozzle *g*¹ adjacent to the nozzle *n* in order to supply an independent supply of oxygen to the acetylene-oxygen flame emitted through the discharge-opening in the nozzle-end. The auxiliary oxygen-supply tube *g* is held 65 in the forked end *f*² by a set-screw *g*² so that the location of the nozzle *g*¹ with respect to the nozzle *n* can be adjusted, the opposite end of the auxiliary tube *g* being provided adjacent the other standard *f* with a swiveled 70 nipple *g*³ into which is screwed a connecting hose *g*⁴ for the oxygen. The end of the auxiliary tube *g* is curved in such a manner that it passes sidewise of the acetylene-supply tube *a* and then over and into line with 75 the nozzle *n*, as shown in Fig. 2.

Having thus described my invention, I claim as new and desire to secure by Letters Patent:

The combination of a tubular receiver having hubs at its ends, an acetylene-tube leading from one end of said receiver, standards applied to said hubs, one of said standards having a forked free end, an oxygen-tube 85 passing through said standards and supported thereby, and an auxiliary oxygen-tube 90 also supported by said standards and adjustably clamped in said forked end.

In testimony, that I claim the foregoing as my invention, I have signed my name in 95 presence of two subscribing witnesses.

AARON FUTTERMAN.
